(57) **CLAIM**

The ornamental design for a four wheeled vehicle body, as shown and described.

DESCRIPTION

FIG. 1 is a front perspective view of a first embodiment of a four wheeled vehicle body;

FIG. 2 is a side perspective view of the four wheeled vehicle of FIG. 1;

FIG. 3 is a left side elevational view of the four wheeled vehicle of FIG. 1, the right side is a mirror image of the left side;

FIG. 4 is a rear perspective view of the four wheeled vehicle of FIG. 1;

FIG. 5 is a front perspective view of a second embodiment of a four wheeled vehicle body;

FIG. 6 is a side perspective view of the four wheeled vehicle of FIG. 5;

FIG. 7 is a side elevational view of the four wheeled vehicle of FIG. 5, the right side is a mirror image of the left side; and,

FIG. 8 is an enlarged fragmentary rear perspective view of the four wheeled vehicle of FIG. 5.

The broken lines are shown for illustrative purposes only and form no part of the claimed design.

FIGS. 1-4 are for a right-hand driven vehicle and FIGS. 5-8 are for a left-hand driven vehicle. Except for the interior components illustrated the outer bodies are substantially identical.

1 Claim, 8 Drawing Sheets

FIG. 4

FIG. 6.

FIG. 8.
